COMBINED TAPE CARTRIDGE PLAYER AND PROGRAMMER CABINET

Melvin H. Boldt, Glenview, Ill., assignor to Automatic Canteen Company of America, Chicago, Ill., a corporation of Delaware

Filed Jan. 27, 1964, Ser. No. 78,378

Term of patent 14 years

(Cl. D26—14)

FIG. 1 is a left side, top and front perspective view of a combined tape cartridge player and programmer cabinet, showing my new design;

FIG. 2 is a right side elevational view, a portion being broken away and in cross-section to show the configuration of the recess in the front surface;

FIG. 3 is a fragmentary top and front perspective view, partly in cross-section taken along the line 3—3 in FIG. 1.

The rear, not shown, is substantially plain and unornamented.

Portions of the drawing figures are shaded to indicate contrast in appearance.

The dominant features of my design reside in the portion shown in full lines.

This application is a continuation-in-part of my application Serial No. D. 70,966, filed July 17, 1962, now abandoned.

I claim:

The ornamental design for combined tape cartridge player and programmer cabinet, as shown and described.
